Primary Examiner — Lauren R Calve(74) Attorney, Agent, or Firm — Banner & Witcoff, Ltd.(57) CLAIM

The ornamental design for a j-cup, as shown and described.

DESCRIPTION

FIG. 1 is a top, front, left perspective view of a j-cup showing our new design;

FIG. 2 is a top, rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depicting the remainder of the j-cup show features that form no part of the claimed design.

1 Claim, 8 Drawing Sheets(56)
